United States Patent Office

Des. 180,160

Patented Apr. 23, 1957

180,160

COFFEE SERVER

Angelo C. Scavullo, Jamaica, N. Y., assignor to Legion Utensils Company, a partnership of New York

Application October 10, 1956, Serial No. 43,306

Term of patent 14 years

(Cl. D44—26)

The single figure is a perspective view of a coffee server showing my new design.

I claim:

The ornamental design for a coffee server, as shown.

References Cited in the file of this patent

UNITED STATES PATENTS

D. 74,138	Burian	Dec. 27, 1927
D. 80,316	Ittig	Jan. 14, 1930
D. 116,248	Stark	Aug. 22, 1939
D. 116,250	Stark	Aug. 22, 1939